VANITY CASE

Filed May 27, 1927

UNITED STATES PATENT OFFICE.

WENDELL M. HAUCH, OF NEW YORK, N. Y., ASSIGNOR TO TERRI INC., OF NEW YORK,
N. Y., A CORPORATION OF NEW YORK.

VANITY CASE.

Application filed May 27, 1927. Serial No. 194,698.

This invention relates to an improved construction of vanity case; and has for its object to provide a case of this general character having lid and body sections hinged together, one of the sections being dished and having side and end walls, an article-carrying tray being located in this section, and an article-carrying member having resilient side walls being forced into the dish section with its resilient walls engaging, pressing and binding the tray into position in the casing section.

A further object of the invention is an arrangement of a pair of trays in spaced relation, the trough-shaped article carrier having resilient side and end walls which are forced into the spaces between the trays to bind them between the walls of the case section and the end walls of the member being arranged to also resiliently grip the walls of the section to assist in binding all of the articles in the case section.

A still further object of the invention is the rolling or turning of the edges of the side walls outwardly forming flanges under which the edges of the powder puff, which overlies the tray, may be gripped and held in position when not in use.

With these and other objects in view, the invention consists of certain novel features of construction as will be more fully described, and particularly pointed out in the appended claims.

In the accompanying drawings:

Figure 1 is a perspective view showing the casing with the lid open and the body portion as containing a pair of trays bound in position by the resilient walls of the central article carrying member.

Figure 2 is a perspective view of the rouge carrying tray in detail.

Figure 3 is a perspective view of the powder compact carrying tray.

Figure 4 is a perspective view of the article carrying trough-shaped binding member.

Figure 5 is a section on line 5—5 of Figure 4 showing the protuberance on the end walls.

Figure 6 is a section on line 6—6 of Figure 5 showing the protuberances on the side walls.

Figure 7 shows a casing for the lip stick

which may be carried in the trough-shaped binding member.

Figure 8 is a perspective view of the lip stick withdrawn from its casing.

Figure 9 is a top view partly in section of the casing with the two trays bound in position by the central trough-shaped binding member against the walls of the body section.

Figure 10 is a section on line 10—10 of Figure 9 showing the rolled edges of the binding member as gripping the edges of the puffs.

Figure 11 is an enlarged view illustrating the protuberances on the end walls of the binding member showing one as engaging a recess in the wall of the body section.

It is found in the practical construction and arrangement of cases of this character of advantage to form one of the sections of the casing with side and end walls and to provide a pair of trays one for the powder compact and the other for the rouge compact of such a size that they may be arranged in spaced relation in the body section of the casing and to provide a binding member preferably of trough shape having resilient side walls the corners of which are disconnected to permit full resiliency of the side and end walls and to snap this member into the space between the trays to bind the trays in position in its casing section also to so form this binding member that it may carry the lip stick and further it is found of advantage to roll the side wall edges of the binding member outwardly so that the puffs overlie the compacts carried in the trays or have their edges pressed under and gripped by these wall edges to bind the puffs in position in the casing when not in use.

By this construction the members of the casing may be readily removed for the purpose of replenishing the trays and new compacts as readily secured in position by simply snapping the binding member between these trays, and the following is a detailed description of the present embodiment of my invention and showing one means by which these advantageous results may be accomplished.

With reference to the drawings, 10 designates the body of the casing which is provided with side walls 11 and end walls 12.

To one of the side walls is hinged at 13 the lid 14 carrying a mirror 15. This casing is especially designed for carrying a number of different toilet articles. I preferably employ a tray 16 having a metal body which is dished for the reception of a powder compact 17. I also employ a tray 18 which is dished for the purpose of carrying a rouge compact 19. These two trays are set into the body section leaving a space between them, and in order to bind these trays in position in the body section I have provided a trough-shaped binding member 20 preferably formed of metal having side walls 21 and end walls 22 and in order to render these walls more resilient I have left them disconnected at their corners as at 23 the marginal edges of these side walls being turned or rolled outwardly as at 24 whereby the rouge and powder puffs 25 may be pressed beneath the rolled edge to bind these puffs in position in the body sections when not in use.

The side walls may be provided with protuberances 26 which will snap over the upper edges of the trays and rest against the bodies thereof, the resiliency of these side walls forcing the trays in opposite directions to bind them against the end walls 12 of the body section.

In some instances in order to cause the side walls of the binding member to more securely grip and retain the side walls of the tray, I may provide recesses 27 in the tray walls for the reception of these protuberances 26, also in some cases I may provide protuberances 28 in the end walls of the binding member to engage the side walls 11 of the body section and in still other instances, I may provide a recess 30 in one of the side walls 11 to receive the protuberance 28 to assist in retaining this binding member in position therein; also in some instances I provide a thumb flange 31 on the binding member by means of which the binding member may be readily removed.

In this binding member I preferably mount a casing 32 as best shown in Figure 7, which is slit at 33 along its upper edge and into this casing is slid the lip stick 34 which is carried in the end clamp 35, the operating button 36 of which may be slid in this slot 33 in the casing.

In some cases, when it is desired, the toilet articles in this body section may be removed and the casing is then of a size and shape to receive cigarettes, if desired.

My improved construction of article-carrying casing and means for retaining the toilet articles is very simple and practical in construction, and by its use these articles may be readily removed from the casing to be replaced by fresh ones.

The foregoing description is directed solely towards the construction illustrated, but

I desire it to be understood that I reserve the privilege of resorting to all the mechanical changes to which the device is susceptible, the invention being defined and limited only by the terms of the appended claims.

70.

I claim:

1. A vanity case comprising lid and body sections hinged together, one section being dished and having end walls, an article carrying tray in said dished section, and a member having resilient walls arranged to engage the walls of said dished section and those of the tray to bind and secure the tray in the dished section.

2. A case having a body section with side and end walls, a pair of spaced trays mounted in said section, and an article carrying member located in the space between said trays and having resilient end walls arranged to engage the walls of the case and resilient side walls shaped to be forced between said trays to bind them against the body walls.

3. A vanity case having a body section with side and end walls, a pair of article carrying trays mounted in said section and an article carrying trough shaped member located between said trays and having resilient end and side walls, the side walls of said member exerting a resilient retaining pressure binding both trays against the walls of the case, and the end walls of said member engaging the wall of the case to bind said member therein.

4. A vanity case comprising lid and body sections hinged together, the body section being dished and having end and side walls, a pair of spaced article carrying trays in the dished section, a sheet metal trough shaped article carrier having resilient end and side walls unattached at their corners and forced into the space between said trays to bind them between the walls of the dished section, and a protuberance on one end wall of said member to engage a depression in the adjacent wall of the section to assist in releasably retaining the member in said section.

5. A vanity case comprising lid and body sections hinged together, the body section being dished and having end and side walls, a pair of spaced article carrying trays in the dished section, a sheet metal trough shaped article carrier having resilient end and side walls and forced into the space between said trays to bind them between the walls of the dished section, and a protuberance on one end wall of said member to engage a depression in the adjacent wall of the section to assist in releasably retaining the member in said section, each of said side walls having a protuberance to snap over and engage with resilient pressure the sides of the opposite trays to press the trays against the walls of the dished section.

6. A vanity case having a body section

120.

125.

115.

120.

125.

with side and end walls, a pair of article carrying trays mounted in said section and an article carrying trough shaped member located between said trays and having resilient end and side walls, the side walls of said member exerting a resilient retaining pressure binding both trays against the walls of the case, and the end walls of said member engaging the wall of the case to bind said member therein, the edges of said side walls being turned outwardly forming edge flanges under which the edge of a powder puff overlying the tray may be gripped and retained. 10

In testimony whereof I affix my signature.
WENDELL M. HAUCH.
